UNITED STATES PATENT OFFICE.

WILLIAM FREEMAN, OF NEW YORK, N. Y.

DESIGN FOR A BUCKLE-PIECE.

SPECIFICATION forming part of Design No. 34,561; dated May 28, 1901.

Application filed February 19, 1901. Serial No. 48,013. Term of patent 14 years.

To all whom it may concern:

Be it known that I, WILLIAM FREEMAN, a citizen of the United States, residing at New York city, county of New York, and State of New York, have invented and produced a new and original Design for a Buckle-Piece, of which the following is a specification, reference being had to the accompanying drawings, forming a part thereof.

In the accompanying drawings, Figure 1 is a view illustrating my new design, and Fig. 2 is an edge view thereof.

The leading or essential feature of my design consists of a strap folded upon itself at one end, forming a flap passed through a slotted plate and depending a limited distance over the face of the body of the strap, and another strap having one end located between the flap of the first-mentioned strap and the upper part of the body of said strap disposed longitudinally on said strap and slotted practically from end to end thereof, and circular ornamentations at the exposed end of the last-mentioned strap and on the flap of the first-mentioned strap, the two straps being 25 free from each other between the said circular ornamentations.

1 represents a strap folded upon itself at one end and passed through the slotted plate 2. The strap 3 is disposed longitudinally on 30 the strap 1 and has one end located between the folded end of the strap 1 and its other end near the other end of strap 1 and is slotted practically from end to end thereof, as shown at 4. The strap 1 is bulged outward 35 or away from the strap 3 between its ends, and circular ornamentations 5 are provided on the exposed end of strap 3 and the folded end of strap 1.

Having described my invention, what I 40 claim as new, and desire to secure by Letters Patent, is—

The design for a buckle-piece herein shown and described.
